UNITED STATES PATENT OFFICE.

JOHN H. WINDHAM, OF UNION, MISSISSIPPI.

GATE-LATCH.

1,286,864.

Specification of Letters Patent.

Patented Dec. 3, 1918.

Application filed May 9, 1918. Serial No. 233,506.

To all whom it may concern:

Be it known that I, JOHN H. WINDHAM, a citizen of the United States, residing at Union, in the county of Neshoba, State of Mississippi, have invented a new and useful Gate-Latch; and I do hereby declare the following to be a full, clear, and exact description of the invention, such as will enable others skilled in the art to which it applies to make and use the same.

The present invention relates to a gate latch operating means and has for its object to provide a device of this character which embodies novel features of construction whereby the latch of a gate can be easily operated from either side of the gate, and without the necessity of stooping down or reaching over the top of the gate.

Further objects of the invention are to provide a gate latch operating means which is comparatively simple and inexpensive in its construction, which can be readily mounted upon any gate and is adjustable to fit different heights of gates, and which can be easily manipulated from the top of the gate.

With these and other objects in view, the invention consists in certain novel combinations and arrangements of the parts as will more fully appear as the description proceeds, the novel features thereof being pointed out in the appended claim.

For a full understanding of the invention, reference is to be had to the following description and accompanying drawing, in which:—

Figure 1 is a front elevation of a gate provided with a gate operating device constructed in accordance with the invention.

Fig. 2 is a perspective view of the swinging end of the gate with the gate operating mechanism mounted thereon.

Fig. 3 is a top plan view of the fulcrum block and operating lever, portions being broken away.

Fig. 4 is an enlarged transverse sectional view through the clamp which is utilized to hold the extensible link member in an adjusted position.

Corresponding and like parts are referred to in the following description and indicated in all the views of the drawings by the same reference characters.

Referring to the drawings, which illustrate one embodiment of the invention, the numeral 1 designates a gate which may be

of any conventional construction, said gate being shown as hingedly connected at 2 to a gate post 3, and as provided at its swinging end with a vertically movable hooked latch member 4 adapted to engage a keeper 5 on the latch post 6. The hooked latch 4 is carried by a plate 7, the rear end thereof being pivotally mounted at 8 between the said plate 7 and a bracket arm 9 projecting therefrom.

A tension spring 10 is connected to the latch member 4 and extends downwardly therefrom, the lower end of the spring being secured to a bracket 11 which is suitably fastened upon the gate. This spring 10 normally tends to swing the latch member 4 downwardly and hold it in operative position.

A fulcrum block 12 is applied to the top of the gate 1 at a point above the latch member 4, the two ends of the fulcrum block being bifurcated, and the said bifurcations being disposed at right angles to each other. The lower bifurcation 12^a fits over the upper edge 80 of the gate and is secured thereto by a suitable fastening member 13. The upper bifurcation 12^b receives the middle portion of a latch operating lever 14 which is pivotally mounted upon a pin 15, the two ends of the lever projecting forwardly and rearwardly respectively from the top of the gate and terminating in the handles 14^a. The middle portion of a spring wire 16 is inserted through the lever 14 at a point adjacent the pivot pin 15, the ends of the spring wire being coiled around the pivot pin on opposite sides of the lever, as indicated at 16^a, and having the extremities thereof embedded in the fulcrum block. This spring 16 serves 95 to normally hold the operating lever 14 in a horizontal position so that either end thereof may be readily grasped by an operator, although it does not interfere with the necessary movement of the lever to manipulate the latch.

An extensible wire link connects the operating lever 14 to the latch 4, said link being formed in upper and lower sections 17 and 18 respectively, the former being pivotally connected at 19 to the operating lever, while the latter is pivotally connected at 20 to the latch. The meeting ends of the link sections overlap each other and each terminates in an eye 21 which slidably receives the other section. At a point between the two eyes 21 the overlapping portions of the wire

link sections are received between the two jaws 22 of a divided clamp member, the gripping faces of the jaws being recessed to receive the link sections, and the two jaws 5 being connected by a clamping screw 23 which passes through the same and has a clamping nut 24 fitted thereon. The effective length of the link can thus be lengthened or shortened as may be found necessary to 10 fit the device upon a tall or a short gate, and the link can be held securely in an adjusted position by means of a clamp 22. When the device is in position, it will be obvious that the latch member 4 can be readily manipulated by moving the operating lever 14 in the necessary manner.

Having thus described the invention, what I claim as new and desire to secure by Letters Patent, is:—

20 The combination with a gate, of a vertically movable latch member at the swinging end of a gate, a fulcrum block at the top of

the gate, a latch operating lever pivotally mounted between its ends on the fulcrum block and projecting forwardly and rearwardly from the gate, a spring carried by the fulcrum block and engaging the operating lever to hold it normally in a horizontal position, and a link connecting the operating lever and the latch member, said link being formed in two sections of which the inner ends overlap each other, each end terminating in an eye which slidably receives the other section, and a clamp engaging the overlapping ends of the two sections 30 to hold them in an adjusted position.

25 In testimony whereof I have signed my name to this specification in the presence of two subscribing witnesses.

JOHN H. WINDHAM.
